NECK BAND IRONER

Mayo Holloway, Birmingham, Ala.

Application April 18, 1936, Serial No. 75,087

10 Claims. (Cl. 38—110)

My invention relates to a device for ironing and setting the neck bands of collar attached shirts.

My present ironer is an improvement on that described in Letters Patent 2,051,854, issued to me August 25, 1936, which is characterized by the provision of a center element adapted to transmit heat to a spring band ironer surrounding, or substantially embracing, it, there being operating means by which the heated band ironer may be first, expanded into firm engagement with the neck band to stretch it, then alternately expanded and contacted to make it slip within the closed neck band so as to iron it, and finally locked in neck band stretching position under tension and in the presence of heat, to set the ironed neck band and collar while the ironing of the shirt body proceeds.

In my said patent is shown a base having pivotally mounted thereon separable heating elements entirely encircled by a single spring ironing band which was caused to expand and contract responsive to the opening and closing of said heating members by suitable spring-pressed actuator means. The band-expanding elements were pivoted at the front of the ironer, and as they were swung apart to expand the band ironer they had a tendency to stretch the neck band laterally out of shape and to displace the front of the shirt forwardly while the iron rested on and held the back of the shirt in place on the ironing board. This displacement will prevent the shirt front from lying smoothly on, or evenly with, the back of the shirt on the ironing board, thereby necessitating the lifting of the ironer to permit a readjustment of the shirt before finish-ironing it. Except in this respect this type of ironer was satisfactory and effective.

One object of my present invention is so to design and mount the expander elements for the spring band ironer as to cause them when expanded not only to set the band ironer in the desired shape for stretching and shaping the neck band, but also, to draw the shirt front back so that it is brought into correct position in which it lies flat on the ironing board and even with the back of the shirt, thus permitting the finish ironing of the shirt to proceed without requiring any readjustment thereof while the ironer is setting the ironed neck band.

A further object of my invention is to form the band heating element as a main block, ovoid in shape and provided with band expanding wings or elements so mounted that as they swing outwardly and backwardly they will cause the band

when expanded to set the neck band with the desired straight back effect.

My invention further contemplates mounting these expander blades or wings so that they collapse into pockets at the back of the ironer block 5 to be heated thereby, and I hinge them preferably near the center of the block so that as they are swung outwardly and rearwardly to expand the ironer band they will thrust it rearwardly and draw the front of the shirt smooth and even on 10 the ironer table and properly adjusted for the finish ironing thereof.

A further advantage of my present invention is that a single heater element can be used in the main block where the ironer is of the self heating 15 type, thus reducing its cost and simplifying its structure.

A further advantage of my invention is that my improved ironer will cause the band throughout its adjustments for different neck sizes to 20 preserve more nearly the correct shape of neck band, than where the block is divided and its half segments are hinged at the front of the ironer.

My invention further comprises the novel details of construction and arrangements of parts 25 which, in their preferred embodiment only, are illustrated in the accompanying drawing, in which:

Fig. 1 is a plan view of my improved ironer set into the closed neck band in position to stretch 30 or set the latter after it has been ironed, the wing operating mechanism being shown in section on the line I—I of Fig. 2.

Fig. 2 is a rear elevation of the ironer with the 35 wings collapsed.

Fig. 3 is a detail sectional view of the guide and latch means for the operating handle.

Similar reference numerals refer to similar parts throughout the drawing.

In the embodiment of my invention illustrated, 40 I show a main ovoid shaped heating block 10, which may be heated in any manner preferably by the introduction of an electric heating element 11 having supply wires 12 leading thereto through a flexible guard 13. This heating element 11 may 45 have any desired shape and be interposed in any practical or satisfactory manner within the block 10. As shown, it is a cylindrical heater set into a suitable opening to receive it near the center of the heating block. 50

Fast in the center of gravity of the heating block 1 mount a vertical standard 14 over the upper end of which is telescoped a vertically reciprocable sleeve 15 that carries at its top the handle 16. The sleeve carries oppositely ex- 55

tending arms 17 having their ends downturned and formed with ball sockets 18 which receive the ball bearings at the upper ends of the crossed arms 19, which arms at their lower ends 5 carry ball bearings engaged in similar ball sockets 20 on the wing expanders 21 for the spring ironing band 22.

These expanders 21 are of duplicate construction and are formed with hinge ears 23 which 10 interleaf between ears formed at the back center of the block 10, and receive their respective hinge pin 24 which pivotally connects each wing to the block.

It will be observed that the wings, when collapsed (see Fig. 2), are received in pockets (see 15 Fig. 1) formed in the rear end of the heating block 10 and terminating short of the base level of the block. Each pocket is formed by a vertical inwardly curved inner wall 25 and a bottom wall 26 formed by an extension of the base 20 portion of the block which conforms to and completes its ovoid shape. When the wings are collapsed each substantially fills its pocket and contacts with the latter's walls 25 and 26. The 25 free tip edge 27 is rounded so that when a wing is in expanded position it will cause the spring ironing band to pass without too sharp a bend from its outer convex edge to the adjacent side edge of the block 10 so that the band 22 will by 30 its own tension, as well as the constraint of the neck band, tend to embrace both elements 10 and 21 thereby to be not only held to its work but maintained heated.

I have shown the band ironer as formed by 35 a single spring band designed to clasp, and when contracted, fully embrace the block 10, but this is merely the preferable arrangement as one or more springs may be effectively employed. I prefer, however, to use the single spring band 40 shaped so that when embracing the collapsed wings and heating block, its free ends will substantially abut at the front tip of the heating block. The spring is loosely connected at its center to the top of the block at the center of 45 its rear end by means of a slotted plate 28 suitably riveted to the top edge of the band above its ironing level and adapted to overhang the top edge of the block so as to receive a guide screw 29 that passes through the slot and connects the band to the block. This loose mounting permits the spring band to be shifted rearwardly bodily when the wings 21 are expanded and to spring forwardly as the wings contract, all the while maintaining snug engagement with 50 the heating block throughout all operating positions except at maximum wing expansion it will bridge a gap formed between the wings. This spring, by its engagement with the block, yieldably resists the expansion of the expander wings 55 21 and therefore serves as a spring to resist the manually applied down thrust from the handle that expands the wings through the cross arms 19, and, when the handle is released, this spring means acts through those arms 19 to restore 60 the sleeve and handle to initial position without requiring an up-pull on the handle that might displace the ironer. It will be understood that any spring means may be used to effect the resetting of the wings 21 and the return of the 65 handle 16 to initial position.

The standard 14 is formed with ratchet teeth 30 thereon and a detent 31 is normally pressed by the spring 32 through a suitable guide 33 on the sleeve into engagement with said teeth. 70 This detent has an operating lever 34 pivoted

on the sleeve in convenient position to be held retracted by the hand that grasps the handle 16. A spring 32 normally presses the detent into engagement with the ratchet teeth. A set screw 36 engages as a key in a slot 37 in the standard 5 15

A collar attached shirt 38 is shown laid out in correct position to present in upright position its neck band 39 which is held closed by a button 40. The ironer, when contracted, is of a size 10 to be conveniently set down into the neck band 15 of the smallest standard size of shirts.

In operation, having set the ironer down in the shirt collar, the handle 16 is grasped, and the handle is pressed down, acting through the cross arms 19 to force the wings 21 rearwardly about their vertical axes so that they will expand the ironer band 22 while pressing its back portion outwardly and also rearwardly against the back of the neck band. The spring pressed detent will engage teeth 30 and hold the wings expanded. This results in a forcing of the yoke and front of the shirt rearwardly and causes a shift in the front yoke seam 41 from its dotted to its full line position shown in Fig. 1. This 20 25 draws the front back so that it lies flat and even on the back of the shirt.

After the ironer has been thus expanded into close engagement within the neck band 39 to stretch the latter, the operator may if desired retract lever 34 and give the handle a few short reciprocating strokes, causing the neck band ironer band 22 to contract and expand again and again, which produces additional slip movements of the heated band relative to and while pressed 35 against the neck band and thus effectively and quickly irons the latter. The spring action of the band working against the tapered sides of the block draws it back to initial position as soon as the handle is released and this resets it and 40 the handle for another positively driven ironing stroke.

When the neck band 39 has been thus sufficiently ironed, the operator releases the ratchet lever 34 and gives the handle a downward thrust 45 which sets the ironer band firmly expanded against the neck band. In this position for average sized shirts the back edge of the band will present almost a straight line across which is the ideal shape for the finished collar opening to 50 best conform to the neck of a wearer. The hot ironer band stands in this expanded position while the operator proceeds to finish the ironing of the shirt in the usual manner, and the time required for the finish ironing will be ample 55 for the hot ironing band to set the ironed neck band. The handle 16 is then grasped, the lever retracted, and the ironer thereupon contracts so it can be lifted by its handle freely from the ironed collar. 60

While I have shown my invention in but one form, it will be obvious to those skilled in the art that it is not so limited, but is susceptible of various changes and modifications, without departing from the spirit thereof, and I desire, 65 therefore, that only such limitations shall be placed thereupon as are imposed by the prior art or as are specifically set forth in the appended claims.

What I claim is:

1. An ironer for neck bands, comprising a block adapted to fit into a closed neck band, a curved spring band ironer adapted to embrace and receive heat from said block, means mounted on the block and movable to guide and expand the 70 75

5 spring band outwardly and rearwardly against the neck band to stretch it, and movable means to actuate said expander means and cause the spring band to form and iron the stretched neck band.

10 2. In an ironer for neck bands, a neck band shaping block comprising a heating element, a curved spring band ironer embracing said block, means mounted for movement rearwardly of said block so as to guide and force the spring band ironer outwardly and rearwardly away from said block to expand it against the back portion of a closed neck band until it stretches the neck band between it and the front end of the block, and means to move said expander means to expand said band ironer outwardly whereby the neck band is ironed.

15 3. An ironer for neck bands, comprising a heating block shaped to form the neck band and adapted for reception in a closed neck band, a spring band ironer and means to mount it in position to embrace and be kept hot by said block and to have bodily movement relative thereto, wings hinged to the larger rear end of the block and movable rearwardly therefrom to expand the band ironer until it stretches the closed neck band, and means to move said wings and impart an ironing movement of the heated band ironer against the stretched neck band.

20 4. An ironer for neck bands, comprising a heating block shaped to form the neck band and adapted for reception in a closed neck band, a spring band ironer and means to mount it in position to embrace and be kept hot by said block and to have free bodily movement relative thereto, wings hinged to the larger rear end of the block near its center and adapted to swing rearwardly therefrom to expand the band ironer until it stretches the closed neck band, and means to move said wings and expand the heated band ironer.

25 5. An ironer for neck bands, comprising a heating block adapted to be freely received in the closed neck band of a shirt, a spring-band ironing means which embraces and presses against the block and is adapted to be heated thereby, means to slidably mount said band for free movement in a given plane rearwardly relative to said block with its free ends when collapsed substantially abutting at the front center of the block, band expander means hinged near the back center of the block, and manually operable means to move said expanders and cause the band means to expand and contract while pressed against said neck band to iron it.

30 6. A neck band ironer comprising a solid ovoid shaped heating block, a vertical standard rigidly mounted in the block close to its center of gravity, a movable actuator slideable on said standard and comprising ratchet means to hold it in a set position, a single arcuate ironing band shaped to tightly embrace said heating block, a slideable connection between the rear larger end of the block near its center to guide the move-

35 ments bodily of said band and the band near its center, rearwardly movable band expanders carried by the rear end of the block, and actuating arms for said expanders having universal joint connection between said actuator and expanders.

40 7. An ironer for neck bands, comprising a neck band former block adapted to be heated and shaped to be freely received in the closed neck band of a collar attached shirt, a spring band ironer embracing and adapted to be heated by said block, means to support said band in operable position free to move bodily rearwardly from said block in a given plane, expander elements pivotally mounted at the rear of the block 45 for rearward swinging movement relatively to said block and adapted by engagement with said band ironer to thrust same bodily rearwardly against the back portion of the neck band, and means to operate said expander elements and cause said band ironer both to expand and stretch the neck band.

45 8. An ironer for neck bands, comprising an ovoid shaped heater block adapted to be freely received in the closed neck band of a collar attached shirt, a spring band ironer embracing said block, means to support said band in operable position free to move bodily rearwardly from said block in a given plane, band ironer engaging elements mounted on and movable outwardly 50 from said block and toward the back of the neck band to effect an expansion of said band ironer until it stretches said neck band and pulls it back, operating means freely reciprocable to actuate said expander elements and impart an ironing movement to the band ironer within a stretched neck band, and means to lock the band expander elements in position to set the ironed neck band.

55 9. An ironer for neck bands, comprising a curved expansible ironer adapted to be received in a closed neck band, an ironer heater means embraced by the band ironer and mounted to provide a fixed thrust bearing for the ironer opposite the front of the neck band, rearwardly movable means to support and expand said band ironer bodily rearwardly and press it against the back of the neck band to stretch the latter, and an actuator to move said band expander means and hold it in position to stretch said neck band.

60 10. An ironer for neck bands, comprising a heater block designed to conform to the normal shape of the front portion of a closed neck band, a curved spring band ironer adapted to embrace and be heated by the marginal edges of said block, means mounted on the block and movable relatively thereto to support and expand the spring band outwardly and shift it bodily rearwardly against the back of the neck band to stretch the latter, and movable means to actuate said expander means and cause the spring band 65 to both stretch and iron the neck band.

MAYO HOLLOWAY.
